PLAY POOL OR SIMILAR ARTICLE

Leonard E. Greenberg, West Hartford, and Joseph Diamond, Simsbury, Conn., assignors to Coleco Industries, Inc., Hartford, Conn., a corporation of Connecticut

Filed Oct. 22, 1965, Ser. No. 87,756

Term of patent 14 years

(Cl. D34—5)

FIG. 1

FIG. 2

FIG. 3

FIG. 4

FIGURE 1 is a perspective view of a play pool or similar article showing our new design;

FIGURE 4 is an end elevational view, the opposite end being the same; and

The dominant features of our design reside in the full line portions of the drawing.

We claim:

The ornamental design for a play pool or similar article, as shown and described.
